M. BAYUK

CIGAR MACHINE

Filed Oct. 17, 1921

FIG. 2.

FIG. 3.

WITNESS:

Robert B. Stetler

INVENTOR

Meyer Bayuk
BY
Frank J. Bussu
ATTORNEY

UNITED STATES PATENT OFFICE.

MEYER BAYUK, OF JENKINTOWN, PENNSYLVANIA.

CIGAR MACHINE.

Application filed October 17, 1921. Serial No. 508,095.

To all whom it may concern:

Be it known that I, MEYER BAYUK, a citizen of the United States, residing at Jenkintown, county of Montgomery, and State of Pennsylvania, have invented a new and useful Improvement in Cigar Machines, of which the following is a full, clear, and exact description, reference being had to the accompanying drawings, which form a part 10 of this specification.

This invention relates to an improvement in cigar machines and more particularly to machines adapted to first wrap the bunch with a binder and then place a wrapper 15 over the binder.

In machines of this type known to me, the bunches are formed by suitable mechanism transferred to the binder applying mechanism and then transferred to the wrapper 20 applying mechanism. These machines require three operators, namely: a bunch maker, a binder cutter, and a wrapper cutter.

The bunch maker merely places the bunch 25 forming material in a suitable position on the feeding mechanism which feeds the material into the bunch forming mechanism, and from which it is transferred to the binder applying mechanism. The binder cutter 30 places a leaf of tobacco, or portions of leaves, on the binder cutting mechanism on which it is cut to shape and is then transferred to the binder applying mechanism. The formed bunch is then transferred to the 35 wrapper applying mechanism, which is also supplied with a wrapper previously removed from wrapper cutting mechanism.

These machines operate very satisfactorily if the bunch forming material is free 40 from hard stems. The bunch forming material contains stems which are frequently severed between the ends of the bunch by the knives, which sever the gauged amount from the fed filler material, and as the severed ends of the stem are at the peripheral portion of the bunch they are liable to be forced through both the binder and the 45 wrapper.

As the cigar is not suitable for smoking, 50 the tobacco is returned to the bunch material and again fed through the machine.

The object of my invention is to provide a machine of this type which can be operated by the same number of operators and in 55 which the loss caused by bad bunches is

eliminated, and thereby not only save the time consumed in making the defective cigars, but also prevent the heavy loss of binders and wrappers which must necessarily be scrapped if the cigar is discarded. 60

I accomplish this by eliminating the filler feeding and selecting mechanism, provide a table for a hand buncher, and provide a bunch conveyor adapted to hold a plurality of hand formed bunches without enclosing 65 them in molds, and convey them to the bunch rolling and binder applying mechanism in timed relation to said mechanism.

The precise nature of my invention will be best understood by reference to the accompanying drawings, which will now be described, it being premised, however, that changes may be made in the construction of the apparatus without departing from the spirit and scope of my invention as defined 70 in the appended claims.

Fig. 1 is a longitudinal view through one form of my improved device, shown somewhat diagrammatically.

Fig. 2 is a plan view thereof; and 80

Fig. 3 is a transverse sectional view through the conveyor.

In these drawings, *a* designates the bunch maker's table which forms a continuation of the conveyor table. The conveyor table 85 comprises side members *b* and intermediate spaced metallic strips *c*, which are secured to cross members *d*. Mounted in suitable bearings on the conveyor table are shafts *e* and *f* having sets of sprocket wheels *g* and *h*, respectively. *i* are sprocket chains, one along each side of the conveyor table, each of which passes around a set of sprocket wheels *g* and *h*, and *k* are suitably spaced metal strips extending from one chain to 90 the other and connected thereto. Connected to each of the metal strips *k* are a plurality of bunch receiving hooks *l* which are adapted to be moved along in the spaces between intermediate table strips *c*. The bases of 100 the hooks are substantially the same width as the spaces between the strips, while the gauge or thickness of the bases of the hooks are substantially the same gauge or thickness as the strips *c*, so that when a formed bunch is inserted in a set of conveyor hooks, the bunch will not only contact with the hooks, but will also be supported by the strips *c*.

The shaft *f* is driven from a shaft *m* of 110

the cigar machine (not shown) so that the chains *i* will make a complete cycle for each twelve cycles of the cigar machine, and as there are twelve sets of conveyor hooks on the conveyor chains, a set of hooks will be moved into delivery position for each cycle of the cigar machine.

n designates a guard secured to the bunch maker's table *a* which extends over the end 10 of the conveyor table at the point at which the conveyor hooks rise through the table, and is arranged to protect the bunch maker from being caught by the hooks as they rise through the table, and also to prevent 15 the insertion of a bunch into the hooks until after they have been moved into the positions in which they move parallel with the conveyor table. *o* is a cigar machine stopping and starting lever located at the side 20 of the bunch maker's table and is arranged to permit the bunch maker to stop the cigar machine if for any reason he cannot make up the bunches as fast as required by the machine and to then start the machine after 25 he has again supplied the conveyor hooks with a supply of bunches. This will enable the bunch maker to stop the cigar machine and prevent the cutting and wasting of binders and wrappers when the supply of 30 bunches is exhausted.

Mounted on suitable pulleys on each side of the conveyor table is a belt *p* which is driven from the cigar machine to move in the reverse direction to the movement of the conveyor, and are arranged to return the scrap cut from the ends of the bunches and transfer it back to the bunch maker's table.

The machine to which I have applied my improved device is provided with bunch 40 transferring fingers carried by arms *q*, and which are adapted to be moved in the planes in which the strips *c* are located. Each transferring finger is provided with a bunch withdrawing end *r* and a bunch ejecting end *s*. *t* are bunch retaining fingers which are in staggered relation to the transferring fingers and are carried by a shaft *u* of the cigar machine. *v* are cutters for cutting the bunches to length and are reciprocated by 45 the cigar machine mechanism in timed relation to the movement to the bunch transferring and the bunch retaining fingers.

The cigar machine is also provided with scrap removing devices *w* which are reciprocated transversely of the conveyor table in timed relation to the cutters *v* to remove the scrap from the cutters to the belts *p*.

The operation is as follows:

When the cigar machine is in operation, 60 the conveyor belt is driven in timed relation to bring a set of conveyor hooks *l* to the point A, for each cycle of the machine.

The bunch maker selects the filler material from a suitable source or sources, manipulates it with his hands to give it the general

shape of a bunch, and after shaping inserts it in a set of hooks while the hooks are moving from A to B.

As the bunch maker manipulates the bunch material with his hands, he can readily detect and remove any substance, such as a stem, which might have a tendency to puncture the binder and wrapper, or position such substance in the bunch so as to avoid the possibility of such puncturing. 70 This manipulation of the filler material not only insures against making punctured cigars, but also permits the manufacture of cigars by machine without unduly moistening the filler material, which frequently occurs when the filling material is fed to the automatic bunch making mechanism of the cigar machine. This is due to the fact that the filler material when bunched by hand need not be moistened to the extent required when bunching by machine, as the buncher's hands are moistened by selecting the bunch material, which moisture will be transferred to the surface of the bunch during the manipulation by the bunch maker.

The finished bunches are successively transferred to the point C by the conveyor and delivered from said point to the point D by the withdrawing ends *r* of the transfer fingers. The bunches are cut to length at the point D by the cutters *v* which are lowered immediately after the bunch has been delivered thereto, and immediately after the cutters *v* are elevated, the scrap removers *w* are manipulated to remove the scrap cut from the ends of the bunch to the belts *p*.

Assuming that the machine is in operation and that the parts are in the positions shown in Fig. 1, the fingers *t* will be retained in the positions shown, while the retracting fingers will be elevated and moved to the left to place the ends *r* in back of the bunch at C and the ends *s* in back of the bunch at D. The retracting members are now lowered and moved to the right to withdraw the bunch from the conveyor hooks at C, transfer it to the point D under the cutters after the bunch under the cutters at D has been ejected by the ends *s* to the point E, D or into the bunch rolling belt F.

During the movement of a bunch from C to D, the fingers *t* will be raised to permit the uncut bunch to pass thereunder and lowered immediately thereafter to retain the bunch under the cutters *v*.

The chains *i* are preferably made of sufficient length so that there is always at least four sets of conveyor hooks on the upper reaches of the chains *i* between the bunch maker and retracting fingers. This provision of a longer upper reach of chains *i* provides means for the reception of a plurality of bunches between the retracting members and the bunch maker and enables the bunch maker to frequently devote more

time in making up troublesome bunches than is required for the making of one cycle of the machine and at the same time supply a bunch to the machine, so long as the time 5 lost in making up troublesome bunches is made up in making subsequent bunches.

This provision for a plurality of bunches between the transfer devices for the cigar machine and the bunch maker permits the 10 continuous operation of the cigar machine without the necessity of the bunch maker inserting a bunch during each cycle of the machine, but permits the bunch maker to frequently spend more time on troublesome 15 material which he can make up on less troublesome material. When operating with normal material, the bunch maker can readily form and place a bunch during each cycle of the machine, but if he should select 20 a bunch of troublesome material he can utilize the time consumed by the machine for making four cycles to make up the troublesome bunch and if the troublesome bunch is inserted in the first set of empty 25 conveyor hooks before the last of the formed bunches is removed he need not stop the machine, and if the following bunches are of good material, he will be enabled to form the bunches more rapidly than required by 30 the machine and in a short time fill all the sets of conveyor hooks on the conveyor table.

Another advantage of my invention results from the provision of a machine which can be operated as rapidly as the automatic 35 machines, and which is so arranged that the bunch maker can select the filler material for each bunch from different sources to make the specified blend, so that all the cigars will be blended in the desired manner.

Having now fully described my invention, what I claim and desire to protect by Letters Patent is:

1. In a cigar making machine, the combination with bunch transferring devices, of a bunch maker's table, a conveyor extending from the table to the transferring devices having a plurality of spaced sets of bunch holding hooks, the hooks of each set being spaced apart to permit the transferring devices to engage the bunches between

the hooks to withdraw the bunches from the hooks and feed them forward, and means for moving the conveyor.

2. A conveyor for a cigar machine for conveying cigar bunches having a plurality of endless sprocket chains, transverse strips connected to the chains, a table above the chains having a plurality of slots, a plurality of hooks connected to each transverse 60 strip arranged to be moved along in the slots, the hooks on each strip forming holders for bunched cigar fillers.

3. A conveyor for a cigar machine having a plurality of shafts, sprocket wheels 65 on said shafts, parallel sprocket chains on the wheels of the two shafts, means for driving one of the shafts, a plurality of spaced strips connected to the two chains, a plurality of spaced conveyor hooks connected to 70 each strip, a conveyor table having spaced slots for the hooks, the parts being so arranged that portions of the table and portions of the hooks act as supports for cigar bunches during a portion of the travel of 75 the chain.

4. A cigar machine having a bunch maker's table, bunch transferring devices, a conveyor between the table and transferring devices, means for driving the conveyor and 80 the transferring devices, and a control device for stopping and starting the driving means adjacent to the table.

5. In a fresh work cigar bunch machine, the combination with means for simultaneously advancing a series of separated charges of long filler, of charge trimming means, and means for successively transferring said charges to said charge trimming 90 means.

6. In a fresh work cigar bunch machine, the combination with means for simultaneously advancing a series of separated charges of long filler in a right line, of charge trimming means, and means for successively transferring said charges still in 95 said right line to said charge trimming means.

In testimony of which invention, I have hereunto set my hand, at Philadelphia, Pa., 100 on this 10th day of October, 1921.

MEYER BAYUK.
